(57) **CLAIM**

We claim the ornamental design for a hockey helmet illuminated display, as shown and described.

DESCRIPTION

FIG. 1 is a back elevational view of a hockey helmet illuminated display.

FIG. 2 is an enlarged bottom plan view of the display.

FIG. 3 is a front elevational view of the display.

FIG. 4 is a top plan view of the display;

and,

FIG. 6 is an enlarged opposite side elevational view of the display.

The broken lines in the drawings depict environmental structure, which forms no part of the claimed design.
